US00D791831S

(12) **United States Design Patent** (10) **Patent No.:** **US D791,831 S**
Capela et al. (45) **Date of Patent:** **** Jul. 11, 2017**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jay Christopher Capela**, Santa Cruz, CA (US); **Alexander Charles MacLean**, San Jose, CA (US); **Parthibhan Mohanraj**, Cupertino, CA (US)

(73) Assignee: **Apple Inc.**, Cupertino, CA (US)

(**) Term: **15 Years**

(21) Appl. No.: **29/546,682**

(22) Filed: **Nov. 24, 2015**

Related U.S. Application Data

(63) Continuation of application No. 29/485,374, filed on Mar. 18, 2014, now Pat. No. Des. 747,728.

(51) **LOC (10) Cl.** **14-04**

(52) **U.S. Cl.**

USPC **D14/493**; D14/492

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines which surround the graphical user interface represent a display screen or portion thereof; the peripheral dashed broken lines form no part of the claimed design.
